Attorney

UNITED STATES PATENT OFFICE.

WILLIAM L. LAUDAN, OF STERLING, COLORADO.

VAPORIZER FOR INTERNAL-COMBUSTION ENGINES.

Application filed January 12, 1924. Serial No. 685,802.

To all whom it may concern:

Be it known that I, WILLIAM L. LAUDAN, a citizen of the United States, residing at Sterling, county of Logan, and State of Colorado, have invented certain new and useful Improvements in Vaporizers for Internal-Combustion Engines; and I do declare the following to be a full, clear, and exact description of the invention, such as 5 will enable others skilled in the art to which it appertains to make and use the same, reference being had to the accompanying drawings, and to the characters of reference marked thereon, which form a part of this 10 specification.

This invention relates to internal combustion engines and has special reference to a vaporizer.

It is well known that in order to obtain 20 the greatest efficiency in the operation of internal combustion engines, it is necessary that the fuel shall be completely vaporized so that it will enter the engine in such form that it will be completely consumed. It is 25 equally well known that the present carburetors permit comparatively large globules of gasoline to enter the combustion chambers of the engine, where they carbonize and form an objectionable deposit instead of developing power.

To obtain greater fuel economy, it has been proposed that some means shall be provided in the intake manifold for separating the unvaporized fuel from the vaporized fuel and to conduct the former to a heated chamber where it is vaporized and from which it is returned to the intake manifold in a gaseous condition.

My invention relates to improvements in 40 the type of devices referred to, one example of which is shown and described in Patent No. 1,474,605 and is designed to overcome certain defects and to perform the additional function of separating dust and dirt 45 from the fuel that enters the engine.

Automobiles and tractors are often required to operate in places where the air is filled with dust and dirt. This enters through the carburetor and passes into the 50 engine where part of it adheres to the walls and forms a grinding compound that causes the cylinder walls and piston rings to wear excessively fast. My device, in addition to its function of separating the unvaporized 55 fuel particles and of vaporizing the same,

also separates the dust particles and prevents them from entering the cylinder.

My invention, briefly described, consists of a separator element introduced in the fuel passage between the carburetor and 60 the intake manifold. This separator is so constructed that the fuel must make a sharp turn in order to enter the intake manifold. Gaseous fuel will make this turn, but unvaporized fuel and dust particles will have 65 such momentum that they will not be able to make the sudden turn required and will continue in their original direction until they reach the bottom of the separator from which they will pass into a settling and 70 vaporizing chamber that is heated by exhaust gases. Here the fuel oil that was precipitated and collected in the separator will be vaporized by heat and will pass through a pipe into the intake manifold while the dirt 75 and dust will remain.

My invention can be most clearly described and will be most readily understood when reference is had to the accompanying drawing in which my invention is illustrated, and 80 in which:

Fig. 1 is a view partly in elevation and partly in section, showing my improved separator and vaporizer attached to the intake and exhaust manifolds; and

Fig. 2 is a detail showing a slight modification.

The same reference characters will be used to designate the same parts throughout the several views.

Numerals 1 designates the intake manifold and 2 the exhaust manifold of an engine, while the carburetor is designated by the numeral 3. Between the intake manifold and the carburetor I place my separator, 90 which consists of a cylindrical member 4 provided at one end with a perforated flange 5, which cooperates with the corresponding flange 6 on the end of the intake manifold. Within the cylindrical member 4 is a tubular 100 member 7 having its upper end closed as indicated by numeral 8 and its lower open end in communication with the opening in the intake manifold. Tubular member 7 is provided with several rows of perforations 105 indicated by numeral 9 and which form the only passage between the carburetor and the intake manifold, except the one through the vaporizing chamber. The bottom of the cylindrical member 4 terminates in a tubular 110

portion 10 which is connected by a pipe 11 to the vaporizing chamber 12. The top of the vaporizing chamber 11 is connected by a pipe 13 with the intake manifold 1. Surrounding the vaporizing chamber 11 is a casing 14 which forms a chamber 15 about the vaporizing chamber. A pipe 16 connects chamber 15 with the exhaust manifold. Heated gases pass through pipe 16 into chamber 15 and out through the opening 17.

The tubular member 7 is preferably provided with a series of outwardly extending downwardly inclined flanges 18. The upper portion of these flanges is located a short distance above the corresponding row of holes 9 so that the gases will have to make an abrupt turn before they can enter the holes 9. In Fig. 2 I have shown how the tubular member 7 can be formed with thick walls through which the holes 9 extend in a diagonal direction with their inner ends above the outer ends. This makes it possible to dispense with the flanges 18.

Let us now consider a case in which the engine is operating and in which fuel is drawn from the carburetor 3. The mixture of vapor, globules of unvaporized oil and dust particles will pass along in the direction of the arrows 19 and will enter the separator. The vapors will make the sudden turns required and pass into the tubular member 7 through holes 9, but the oil globules and dust particles, owing to their superior mass and momentum, will not be able to make the sudden reversal in directions required and continue their downward course until they finally enter the tubular bottom portion 10 and pass through the pipe 11 into the vaporizing chamber 12 where the oil will be vaporized by the heat and will pass on as vapor into the manifold 1. The dust particles will remain in the chamber 12 until removed therefrom.

It is evident from the above that any unvaporized oil or gasoline entering the separator will be removed from the gaseous portion and conducted to the vaporizing chamber 12 and that sand or dirt particles will be removed in the same manner, thus assuring that the explosive mixture that enters the engine shall be thoroughly vaporized and clean.

Having now described my invention, what I claim as new is:

55 1. A device for separating unvaporized oil and dust particles from a fuel mixture, comprising a cylindrical member open at both ends, a tubular member located within the cylindrical member and spaced from the sides thereof, said tubular member having one end closed and the other end open and connected to the wall of the cylindrical member, which is adapted to register with an opening in an intake manifold, said tubular member having a plurality of rows of holes,

means comprising conical flanges for causing gases to make a sharp turn when passing from the space in the cylindrical member to the inside of the tubular member, and a cap, having a cylindrical conduit, connected to the open end of the cylindrical member and adapted to be connected with a carburetor. 70

2. A device for separating unvaporized oil and dust particles from a fuel mixture, comprising a cylindrical member open at both ends, a tubular member located within the cylindrical member and spaced from the sides thereof, said tubular member having one end open and the other closed, said open end being adapted to register with an opening in an intake manifold of an internal combustion engine, said tubular member having a plurality of rows of holes, means for causing gases to make a sharp turn when passing from the space in the cylindrical member to the inside of the tubular member, said cylindrical member being provided at its bottom with an opening adapted to serve as an exit for the particles separated from the gas and a cap, having a cylindrical conduit, secured to the open end of the cylindrical member nearest the carburetor and adapted to connect it with the carburetor. 85 90

3. A device for separating unvaporized oil and dust particles from a fuel mixture, comprising a cylindrical member open at both ends, a tubular member located within the cylindrical member and spaced from the sides thereof, said tubular member having one end open and the other closed, said open end being adapted to register with an opening in an intake manifold of an internal combustion engine, said tubular member having a plurality of rows of holes, means for causing gases to make a sharp turn when passing from the space in the cylindrical member to the inside of the tubular member, said means comprising a plurality of conical flanges projecting downwardly below the holes, and a cap secured to the open end of the cylindrical member, nearest the carburetor, said cap having a conduit connecting it to a carburetor. 100 105 110

4. A device for separating unvaporized oil and dust particles from the fuel mixture, comprising a cylindrical member open at both ends, a tubular member located within the cylindrical member and spaced from the sides thereof, said tubular member having one end open and adapted to register with an opening in an intake manifold, said tubular member having a plurality of rows of holes, means comprising outwardly and downwardly extending flanges for causing gases to make a sharp turn when passing from the space in the cylindrical member to the inside of the tubular member and a cap secured to the open end of the cylindrical member nearest the carburetor, and 115 120 125 130

a conduit connecting said cap to a carbureter.

5. A device for separating unvaporized oil and dust particles from a fuel mixture, comprising a cylindrical member open at both ends, a tubular member within said cylindrical member, said tubular member having one end closed and the other end open, the open end of the tubular member 10 being secured to the cylindrical member at a point opposite from the open end of the latter, means comprising a flange for securing the open end of the tubular member to the end of an intake manifold, said tubular member having a plurality of rows of openings which connect the interior of the cylindrical member with the interior of the tubular member, and a flange corresponding to each row of holes, said flanges being inclined and project over the holes in such a manner that air as it flows from the cylindrical chamber to the interior of the tubular member, must make a turn of more than 90 degrees whereby a separating action 20 will take place between the gaseous and non-gaseous particles and a cap secured to one of the open ends of the cylindrical member,

said cap having a conduit adapted to extend to and be connected with a carburetor.

6. A device for separating unvaporized oil and dust particles from a fuel mixture, comprising a cylindrical member open at both ends, a tubular member within said cylindrical member, said tubular member having one end closed and the other end open, 30 the open end of the tubular member being secured to the cylindrical member at a point opposite from the open end of the latter, means comprising a flange for securing the open end of the tubular member to the end 35 of an intake manifold, said tubular member having a plurality of rows of openings which connect the interior of the cylindrical member with the interior of the tubular member, a flange corresponding to each row of holes, 40 each of said flanges being inclined so as to project over the corresponding row of holes, a cap secured to the one of the open ends of the cylindrical members, said cap having a cylindrical conduit adapted to extend to 45 and be connected with the carburetor.

In testimony whereof I affix my signature.

WILLIAM L. LAUDAN.
